UNITED STATES PATENT OFFICE.

GEORGE E. PURPLE, OF LA GRANGE, ILLINOIS, ASSIGNOR TO FLEXIBLE STEEL LACING COMPANY, OF CHICAGO, ILLINOIS, A CORPORATION OF ILLINOIS.

BELT-LACING MACHINE.

Application filed July 23, 1927. Serial No. 207,920.

This invention relates to improvements in belt lacing machines.

In a number of industries, it is necessary to use belts, aprons or conveyors of relatively great width, as for instance, in laundries where the belts or aprons may be from 6 to 10 feet or more in width. With belts of such width, the item of time required to apply the belt lacings or belt fasteners when putting on a new belt or repairing an old one, is of considerable importance and economical practice requires that the lacing or fasteners be applied as quickly as possible and with a minimum of labor.

One object of my invention therefore, is to provide a belt lacing machine capable of taking belts or aprons of wide width and in which means are provided for rapidly attaching and clinching the lacings or fasteners across the entire width of the belt or apron end.

Another object of my invention is to provide automatically operating, power-actuated means for progressively and successively bending, attaching and clinching the belt lacings or fasteners across the full width of the belt or apron end whereby the entire lacing or series of fasteners is applied in a most expeditious manner.

Still another object of my invention is to provide a machine of the character indicated wherein the entire length of lacing or fasteners may be applied during one cycle of movement only of the machine.

Other objects of the invention will more clearly appear from the description and claims hereinafter following.

Broadly speaking, the preferred embodiment of my invention contemplates a suitable framework, on which is supported the desired length of belt lacing holder corresponding to the maximum width of belt or apron for which the machine is adapted and a carriage supported on the framework and movable lengthwise of the lacing holder, said carriage having mounted thereon and movable therewith a plurality of sets of rollers, the sets of rollers being so arranged that the first set to engage the belt lacings partially deforms them and the lacings are then successively and progressively further deformed, attached and ultimately clinched as the carriage moves across the machine. The preferred form also contemplates the positive rotation of the attaching rollers during their bodily movement across the machine and power-actuated means for moving the carriage.

In the drawings forming a part of this specification, Figure 1 is a front elevational view of the machine showing my improvements in connection therewith. In this view, certain parts are broken away to better accommodate the view on the sheet and to more clearly illustrate certain parts. Figure 2 is a vertical, transverse, sectional view, upon an enlarged scale corresponding approximately to the section line 2-2 of Figure 1, the view being taken in the direction indicated by the arrows. Figure 3 is a top plan view, corresponding to the line 3-3 of Figure 1 and illustrating more particularly the carriage and parts mounted thereon. Figure 4 is a vertical, sectional view corresponding to the section line 4-4 of Figure 1 and upon the same scale as Figure 2. Figure 5 is a horizontal, sectional view, more particularly illustrating the gearing for driving the rollers and corresponding approximately to the section line 5-5 of Figure 1. Figure 6 is a vertical, sectional view, upon an enlarged scale, corresponding approximately to the section line 6-6 of Figure 1. Figure 7 is a vertical, sectional view, parts broken away and corresponding approximately to the section line 7-7 of Figure 3. Figure 8 is a detailed, vertical, sectional view taken through a set of rollers and corresponding approximately to the section line 8-8 of Figure 3. Figure 9 is a horizontal, sectional view corresponding to the section line 9-9 of Figure 8. Figure 10 is a top plan view, parts broken away, upon an enlarged scale, illustrating more particularly the lacing holder with a section of belt lacing in place and a portion of the belt or apron, the latter being in section. Figure 11 is a longitudinal vertical, sectional view, through the center of the lacing holder with one of the holding plates removed to better expose the interior arrangement. Figure 12 is an elevational view of a portion of a belt or apron showing a section of the lacing applied thereto. Figures 13, 14, 15 and 16 are enlarged, detail, vertical, sectional views corresponding to the section lines 13-13, 14-14, 15-15 and 16-16 respectively, of Figure 1, and illustrating the belt lacing holder, the lacing, and the successive sets of progressive rollers and the manner of deforming and applying the belt lacing.

In carrying out my invention, a suitable supporting framework for the parts is provided, the same consisting of two vertical end castings 20—20, united by a series of hollow tubes or bars 21—21, the attachment between the latter and the end frames being by any suitable means such as the flanged nipples 22 threaded to the tubes 21 and bolted to the end frames. In addition, a heavy rail 23 is extended between and connected at its ends to the end frames 20, said rail 23 being of plate-like form arranged vertically as best indicated in Figure 2 and braced against bending by any suitable means such as the angle iron 24 secured thereto and lengthwise thereof. A supporting bar 25 is also extended between the end frames 20 and detachably secured thereto as by bolts 26, by which the ends of said bar are attached to suitable shelves or ledges preferably cast integral with the end frames. Said bar 25 has secured to the underside thereof an elongated, stationary rack 27 for the purpose herein-after described. Also secured to the upper side of said bar 25 is the lacing holder indicated generally by the reference character A and described more in detail hereinafter.

The movable carriage, indicated generally by the reference character B, preferably comprises a casting of more or less irregular contour to provide the necessary shaft bearings for the parts and a specific description of which is not deemed necessary. Said carriage B is arranged to be supported in its back and forth movements partly on the rail 23 by means of the grooved roller 28 which straddles and rests upon the upper edge of said rail 23, said roller 28 being suitably journaled in a depending bracket 29, attached to the main carriage B. By means of said roller 28, it will be evident that the carriage B is not only supported, but is also guided so as to be prevented from twisting or turning in its back and forth movements. Further, additional supporting and guiding means for the carriage B are provided in the three upper guiding and supporting flanged rollers 30, 31 and 32, suitably journaled to the carriage B so as to rotate about horizontal axes, the rollers 30 and 31 being on the back side of the carriage and the roller 32 on the front side thereof and rolling upon the upper surfaces of the bar 25. As will be obvious, the flanges of said rollers serve to confine the movements of the carriage B to a straight line parallel with the bar 25.

In the preferred form of the invention, the carriage B is positively moved in its travel across the machine and to this end, I provide, on the bottom of the carriage B, any suitable electric motor 33, the armature of which carries a sprocket gear 34 on the front side of the machine and over which rides a chain belt 35, the latter cooperating with a second sprocket gear 36 at the lefthand

end of the carriage B as viewed in Figure 1. The sprocket gear 36 is attached to a shaft which is extended within a housing 37, best shown in Figure 2 and within which is any suitable type of reduction gearing, the power being ultimately delivered from the reduction gearing through a shaft carrying a pinion 39, which, in turn, meshes with a larger pinion 140 carried by a horizontally extending shaft 40 suitably journaled in the carriage B. Referring more particularly to Figure 2, the opposite end of said shaft 40 carries a pinion 41, which in turn, meshes with another pinion 42 secured to an upper cross shaft 43 journaled in the carriage B, the inner end of said shaft 43 in turn having a gear wheel 44 secured thereto which meshes with the stationary rack 37 so that the motor 33 is thus adapted to impart positive movement to the carriage B at the desired reduced speed.

In the preferred embodiment of the invention, three sets of rollers are employed arranged in series so as to progressively apply the belt lacing as hereinabove described in detail. Each of these rollers is preferably positively rotated by the following mechanism:

Starting with the shaft 40, reference being had to Figures 2, 4, 6 and 7, it will be observed that said shaft 40 carries, near each end thereof, just within the pinions 140 and 41, two bevel gears 45 and 46, respectively. The bevel gear 45, in turn, meshes with a bevel gear 47 carried by the lower end of a vertically extending roller shaft 48, the latter being suitably journaled in the carriage B. The shaft 48, as best illustrated in Figure 6, has secured thereto, a gear 49 which meshes with an intermediate pinion 50, the latter in turn meshing with a gear 51 carried at the lower end of the vertical shaft of the next adjacent roller. The gear 51, in turn, meshes with another pinion 52 and the latter, in turn meshing with a gear 53 carried by the lower end of the shaft for the righthand end roller, as viewed in Figure 7. There is thus imparted a positive drive to each of the three rollers of the series on the back side of the machine. Similarly, a positive drive and at the same speed is imparted to the three complementary rollers on the front side of the machine from the bevel gear 46 through the bevel gear 54 (see Fig. 6) to the lower end of the vertical shaft 55 for the lefthand roller of the series on the front side of the machine as viewed in Figure 1. Said shaft 55 in turn, carries a gear 56 which, through the intermediary of pinion 57, gear 58, pinion 59 and gear 60, drives the two remaining rollers of the series on the front side of the machine, as viewed in Figure 1.

To accommodate variations in the thickness of the belt or apron having the belt lacing applied thereto, it is desirable to provide

slight adjustment for each of the rollers and this is accomplished by the ball bearing arrangement for the upper ends of the roller shafts as illustrated in detail in Figures 8 and 9. In said figures, it will be noticed that the upper end of each roller shaft is encircled by an anti-friction, ball bearing set of rings 61, the latter being accommodated in somewhat larger recesses 62 provided in the carriage casting B. Each ball bearing ring arrangement is adjustably limited in its outward movement away from the center line of the machine by an adjusting screw 63 adapted to be held in adjusted position by lock nut 64. In this manner, the spacing between the rollers of each pair, as illustrated in Figure 8, can be varied and accommodated to variations in the thickness of the work being acted upon and, in addition, as will be apparent to those skilled in the art, an anti-friction bearing is also simultaneously provided.

As best shown in Figure 1, I provide a limiting stop shoulder 65 on the righthand end frame 20 to limit the movement of the carriage B to the right, the latter having a cooperating shoulder 66. To limit the movement of the carriage to the left, a second stop shoulder 67 is provided on the lefthand end frame 20, and with which the end shoulder 68 of the carriage is adapted to engage for that purpose.

The lacing holder A is preferably comprised of a series of unit lengths, the total length corresponding to the maximum width of belt or apron to which the lacing is to be applied. In order to mount the lacing holder, the bar 25 is preferably centrally grooved on its upper face as indicated at 69 in Figure 2 and inserted in this groove is a longitudinally extending bar 70 having a recess 71 cut along the top face thereof. As best shown in Figures 13 to 15, this recess 71 is of right angular cross-section and tilted with respect to the vertical so as to provide a lower surface 72 inclined at approximately 30° to the horizontal and another longer face 73 inclined upwardly at approximately 60° to the horizontal. Within the groove 71 thus formed are secured the desired number of unit sections that comprise the lacing holder. The lacing holder is formed, as best shown in Figures 13 to 16, by an inner plate-like member 74 which lies against the groove surface 73 and another comb or holding plate 75, which bears against the member 74 and rests at the bottom against the surface 72, the parts being held in position by a series of screws, as indicated in Figure 1. The holding member 75, along its upper edge, is provided with a series of slots or recesses 76 with intervening partitions 77 adapted for the reception of the belt lacing indicated at 78. The latter is ordinarily formed of general V-cross-section as indicated in Figure 13, with inwardly extended opposed prongs 79. The lacing 78 is adapted to be temporarily held in

position in the customary manner by a longitudinally extending pin 80 which passes through aligned perforations in the partitions 77 and which seats within the apex of the lacing, as clearly shown in Figure 13. The upper edges of the partitions 77 are chamfered as indicated at 81.

To facilitate handling of the belt or apron, the latter is rolled up as indicated at 83 in Figure 2 and supported by a series of loops 75 183 suspended on the two upper tubes 21 of the main frame, the free edge of belt being brought down to a point within the lacing, as shown in Figures 13 and 16. In the drawings, I have illustrated a belt or apron of 80 comparatively light stock, in which case the end of the belt or apron is generally folded over on itself so as to provide a double thickness to receive the prongs of the belt lacing.

Referring next to Figures 1 and 14 to 16, 85 it will be observed that the righthand set of rollers 84-84, as viewed in Figure 1 and shown in detail in Figure 14, have plane, vertical edges 85 arranged in parallelism. The next or intermediate series of rollers 90 86-86 have their edges so formed as to present a vertical face 87 from the top approximately to the middle and from the latter, the faces are beveled off as indicated at 88 so as to present a downwardly flaring mouth, as 95 shown in Figure 15. The final or lefthand set of rollers 89-89, as viewed in Figure 1 and shown in detail in Figure 16, have plane, vertical edge faces 90, but are disposed much closer together than the operative faces of 100 the rollers 84 shown in Figure 14.

The operation of the machine is as follows, assuming the necessary length of belt lacing has been inserted in the holder and the belt end brought into position for attaching the lacing. The carriage B will be started from the lefthand end of the frame as viewed in Figure 1 and will advance toward the right, being positively driven from the motor as hereinbefore described. As the advance set of 110 rollers 84 engage the prongs of the belt lacing, the prongs will be deflected or bent inwardly toward each other so as to partially enter the prongs into the belt or apron as shown in Figure 14. As will be understood, 115 the advance set of rollers will accomplish this action for the entire length of belt lacing as the carriage progresses across the machine. As the second set of rollers 86 come into engagement with the belt lacing, the beveled edges 88 thereof will still further force the prongs of the lacing toward each other and into the belt or apron and start the deflecting or turning of the free ends of the prongs, as shown in Figure 15, this step 120 in the clinching operation taking place for the full length of the lacing as the carriage travels across the machine. The final set of rollers 89 will complete the turning over and 125 imbedding of the prongs of the lacing into 130

the fabric and finish the clinching as illustrated in Figure 16. It will thus be seen that the three sets of rollers act progressively on the belt lacing and successively deflect and clinch the lacing in a continuous operation as the carriage B traverses the machine so that the entire lacing is applied quickly, automatically in one cycle of operations.

In actual practice, the pitch diameter of 10 the gear wheel 44 and its speed of rotation will be so related to the peripheral speed of 15 the clinching rollers that the lineal speed of travel of the carriage B will equal the peripheral speed of said rollers, so that there will be no slippage of the rollers relative to the lacing, thus avoiding any distortion of the lacing and reducing the friction to the minimum. Further, by providing a motor 20 drive for the carriage, all the attention of the operator may be given to the holding of the belt or apron in proper position, thus facilitating the work.

In the drawings, I have illustrated the machine as adapted for applying belt lacings to wide belts but, as will be obvious to those skilled in the art, many of the features of my improvements are applicable to smaller size machines or devices. In the drawings have been illustrated one well known form of belt lacing and to which the latter term is correctly technically applied. As will be understood by those skilled in the art, other forms of belt lacings or what are technically known as belt fasteners of the staple type may be 35 applied in my machine without any departure from the invention and in the appended claims, the term "belt lacing" is employed in the broad sense to include any type of belt lacing or fastener.

I am aware that many changes and variations may be made in the details of construction and arrangement of parts without departing from the spirit of the invention and all such changes and modifications are contemplated as come within the scope of the claims appended hereto.

I claim:

1. In a belt lacing machine, the combination with a frame having means thereon for holding belt lacing; of a carriage mounted on said frame to move lengthwise of said holding means; and means entirely on said carriage movable therewith and positioned to engage opposite sides of the lacing and operable by the movement of the carriage to clinch the lacing to the end of a belt or the like.

2. In a belt lacing machine, the combination with a frame having means thereon for holding belt lacing; of a carriage mounted on said frame to move lengthwise of said holding means; a motor mounted on said carriage; gearing between said motor and frame operative to positively move said carriage; and means mounted on the carriage for

clinching the lacing to the end of a belt or the like.

3. In a belt lacing machine, the combination with a frame having means thereon for holding belt lacing; of a carriage mounted on said frame to move lengthwise of said holding means; and a plurality of sets of devices on said carriage and movable therewith arranged to successively act upon the belt lacing and progressively clinch the same as the carriage moves lengthwise of the holding means.

4. In a belt lacing machine, the combination with a frame having means thereon for holding belt lacing; of a carriage mounted on said frame to move lengthwise of said holding means; and a plurality of sets of devices on said carriage and movable therewith arranged to successively act upon the belt lacing and progressively clinch the same as the carriage moves lengthwise of the holding means, each said set of devices including a pair of opposed cooperable rollers.

5. In a belt lacing machine, the combination with a frame having means thereon for holding belt lacing; of a carriage mounted on said frame to move lengthwise of said holding means; a plurality of sets of devices on said carriage and movable therewith arranged to successively act upon the belt lacing and progressively clinch the same as the carriage moves lengthwise of the holding means, each said set of devices including a pair of opposed cooperable rollers; and means for positively rotating said rollers about their individual axes while the carriage is moving.

6. In a belt lacing machine, the combination with a frame having means thereon for holding belt lacing; of a carriage mounted on said frame to move lengthwise of said holding means; a plurality of sets of devices on said carriage and movable therewith arranged to successively act upon the belt lacing and progressively clinch the same as the carriage moves lengthwise of the holding means; a motor mounted on said carriage; and reduction gearing between said motor and frame operative to positively move said carriage lengthwise of said holding means.

7. In a belt lacing machine, the combination with a frame having means thereon for holding belt lacing; of a carriage mounted on said frame to move lengthwise of said holding means; a motor mounted on said carriage; gearing between said motor and frame operative to positively move said carriage; a plurality of sets of devices on said carriage arranged to successively act upon the belt lacing and progressively clinch the same, each said set comprising a pair of opposed rollers and means for positively rotating each of said rollers.

8. In a belt lacing machine, the combination with a frame having means thereon for holding belt lacing; of a carriage mounted

on said frame to move lengthwise of said holding means; means, movable with said carriage, directly engageable with the belt lacing and successively, progressively operative thereon to clinch the lacing as the carriage moves lengthwise of the lacing holding means; a prime mover; and operating means actuated by said prime mover for positively effecting movement of the carriage.

10. 9. In a belt lacing machine, the combination with a frame having means thereon for holding belt lacing; of a carriage mounted on said frame to move lengthwise of said holding means; a prime mover; operating means actuated thereby for positively effecting movement of the carriage; and means, actuated upon movement of the carriage, for clinching the belt lacing to a belt.

10. 10. In a machine of the character described, the combination with a holder for belt lacing; of a series of sets of devices, the series being arranged lengthwise of the holder and each set of devices including two elements, one at each side of the lacing and engageable therewith, the sets being individually adjusted in sequence to progressively clinch the lacings; and means for effecting relative movement between said holder and said series of devices.

20. 11. In a machine of the character described, the combination with means for holding belt lacing; of a series of pairs of rollers, the series being arranged lengthwise of said means, the rollers of each pair being disposed on opposite sides of the holding means and adapted to engage with the belt lacing, the pairs of rollers being so arranged in sequence as to progressively clinch the lacing; and means providing for relative longitudinal movement between said holding means and series of rollers.

25. 12. In a machine of the character described, the combination with means for holding belt lacing; of a series of pairs of rollers, the series being arranged lengthwise of said means, the rollers of each pair being disposed on opposite sides of the holding means and adapted to engage with the belt lacing, the pairs of rollers being so arranged in sequence as to progressively clinch the lacing; means providing for relative longitudinal movement between said holding means and series of rollers; and means for positively rotating said rollers during the relative movement between said holding means and series of rollers.

30. 13. In a machine of the character described, the combination with a holder for belt lacing; of a series of sets of devices, the series being arranged lengthwise of the holder and each set of devices including two elements, one at each side of the lacing and engageable therewith, the sets being individually adjusted in sequence to progressively clinch the lacings; means for effecting rela-

tive movement between said holder and said series of devices; and means for adjusting the effective distance between the elements of each pair.

14. In a machine of the character described, the combination with means for holding belt lacing; of a series of pairs of rollers, the series being arranged lengthwise of said means, the rollers of each pair being disposed on opposite sides of the holding means and adapted to engage with the belt lacing, the pairs of rollers being so arranged in sequence as to progressively clinch the lacing; means providing for relative longitudinal movement between said holding means and series of rollers; means for positively rotating said rollers during the relative movement between said holding means and series of rollers; and means for individually adjusting each of said rollers whereby to vary the effective distance between rollers of each pair.

15. In a device of the character described, the combination with a frame having a holder fixedly mounted thereon, the holder having a substantially V-recess to receive the lacing; of a carriage; means for effecting relative movement between said carriage and holder; and means, including a roller, mounted on said carriage and adapted to engage the lacing to clinch the latter upon relative movement of the holder and carriage.

16. In a belt lacing machine, the combination with a frame having a bar extended lengthwise thereof; a belt lacing holder mounted on said bar in fixed position; a carriage slidably mounted on said frame lengthwise of said bar; and a series of devices mounted on said carriage and movable therewith, arranged to successively engage lacing held by said roller and progressively deform and clinch the same in the movement of the carriage on the frame.

17. In a machine of the character described, the combination with a supporting frame having a bar extending lengthwise thereof; of a lacing holder mounted on the upper side of said bar in fixed position thereon; means on said framework for supporting a portion of a belt above said holder; a carriage slidably mounted lengthwise of said bar; means mounted on said carriage for clinching the lacing as the carriage moves lengthwise of the bar; and mechanism for positively moving the carriage.

18. In a machine of the character described, the combination with means for holding a belt lacing; of a pair of rollers positioned adjacent said holding means and adapted to operate on lacing held thereby, said rollers being carried by journals; and means for adjusting the effective distance between said rollers.

19. In a machine of the character described, the combination with a framework; of a lacing holder supported in fixed position on said framework and extending lengthwise there-

of; a carriage movable lengthwise of said framework; a motor mounted on said carriage; gearing between said motor and framework for effecting movement of the carriage lengthwise of the framework; a series of pairs of rollers located adjacent said holder and adapted to engage lacing held thereby; and means for positively rotating each of said rollers during movement of the carriage lengthwise of the framework.

20. In a machine of the character described, the combination with means for holding belt lacing; of a series of pairs of rollers adapted to engage with the belt lacing in succession and progressively clinch the lacing; power driven means providing for relative lineal movement between said holding means and the series of rollers at a given lineal speed; and means for positively rotating said rollers with a peripheral speed corresponding to that of said lineal speed.

21. In a belt lacing machine, the combination with a frame having means thereon for holding belt lacing; of a carriage mounted on said frame to move lengthwise of said holding means; a prime mover; a plurality of

pairs of rollers mounted on said carriage and bodily movable therewith and adapted to engage the belt lacing and progressively clinch the latter; and gearing between said prime mover and rollers and between said prime mover and frame for imparting rotation to said rollers and lineal movement to said carriage with a peripheral speed of the rollers corresponding to the lineal speed of said carriage.

22. In a belt lacing machine, the combination with a frame having means thereon for holding pronged belt lacing, of a carriage mounted on said frame to move lengthwise of said holding means, means movable with said carriage and including members embracing the lacing and acting on opposite sides thereof and spaced to insure a closing of the lacing by the passage of said members as the carriage is moved, said members being operative on the lacing to clinch the same by pressure exerted from opposite directions thereon.

In witness that I claim the foregoing I have hereunto subscribed my name this 14th day of July, 1927.

GEORGE E. PURPLE.
